UNITED STATES PATENT OFFICE.

ANTOINE J. LANGEIER, OF PROVIDENCE, RHODE ISLAND.

MACHINE FOR MAKING BLANKS FOR SEWING-MACHINE NEEDLES OR SIMILAR ARTICLES.

SPECIFICATION forming part of Letters Patent No. 665,830, dated January 1, 1901.

Application filed December 18, 1899. Serial No. 740,796. (No model.)

To all whom it may concern:

Be it known that I, ANTOINE J. LANGEIER, a citizen of the United States, residing at Providence, in the State of Rhode Island, have 5 invented a new and useful Improvement in Machines for Making Blanks for Sewing-Machine Needles or Similar Articles, of which the following is a specification.

My invention consists in an improved automatic machine wherein a sewing-machine-needle blank may be fully completed ready for the subsequent operations of forming the eye and pointing.

In the accompanying drawings, Figure 1 represents a side elevation of the machine. Fig. 2 represents a top view of the same. Fig. 3 represents a rear end view. Fig. 4 represents a forward end view. Fig. 5 represents a partial longitudinal vertical section taken 20 in the line A A of Fig. 2, the rotary carrier and portions of the frame being shown in elevation. Fig. 6 represents a detail view and section showing the mechanism for rotating and locking the carrier, the section being 25 taken in the line B B of Fig. 1. Fig. 7 represents a vertical section taken in the line C-C of Fig. 1. Fig. 8 represents a vertical section taken in the line D D of Fig. 1. Fig. 9 represents a top view of the rotary carrier 30 and the cams by means of which the sliding spindles of the carrier are actuated. Fig. 10 represents an enlarged detail section taken in the line E E of Fig. 7. Fig. 11 represents a detail sectional view taken in the line F F of Fig. 10, showing the cam-slot in the slide 35 which serves to cut off the blank from the continuous wire and transfer it to the holding-jaws of the revolving carrier. Fig. 12 represents an enlarged longitudinal section 40 of the sliding clamp for feeding the wire from the coil, taken in the line E E of Fig. 7. Fig. 13 represents an enlarged transverse section of the sliding clamp, taken in the line G G of Fig. 10. Fig. 14 represents a top view of the 45 yielding connecting-piece by means of which the feeding mechanism is operated. Fig. 15 represents an enlarged side view and partial section showing a portion of the mechanism for delivering the severed blank to the rotary 50 carrier; also, showing a detail longitudinal vertical section of the carrier and a longitudinal vertical section of the rotary spindle

which carries the tool for milling the rear end of the needle-blank before it is severed from the wire of the feeding-coil, together with a 55 side view of the cam for actuating the said rotary spindle in the forward direction and a detail side view of the means for operating the said cam. Fig. 16 represents a top view and partial section of the pivoted frame which 60 holds the rotary spindle for milling the rear end of the needle-blank. Fig. 17 represents a section taken in the line H H of Fig. 16, the turned upright position of the pivoted frame which holds the milling-spindle being shown 65 in dotted lines. Fig. 18 represents an enlarged end view, and Fig. 19 corresponding side views, taken at right angles to each other, of the holder for the tool employed in milling the rear end of the blank before it is cut off from the 70 continuous wire from which it is to be formed. Fig. 20 represents enlarged side views, taken at right angles to each other, of the cutting-tool employed for milling the end of the wire. Fig. 21 represents the side view of a piece of 75 wire having its end milled in conical shape, by means of the tool shown in Fig. 20, to form a needle-blank. Fig. 22 represents an enlarged detail sectional view showing the end portion of the rotary spindle in which the 80 tool-holder and the milling-tool are held. Fig. 23 represents a section, taken in the line I I of Fig. 15, showing the operating means for clamping the wire which is being fed to the machine. Fig. 24 represents a detail horizontal section, taken in the line J J of Fig. 15, showing the wedge for closing the holding-jaws of the carrier-spindle upon the 85 needle-blank, and Fig. 25 represents a rear view of the said wedge and also a section taken 90 transversely of the sliding spindle upon which the wedge is arranged to act. Fig. 26 represents a detail section of the frame of the machine, taken in the line K K of Fig. 7, also showing the pushers by means of which 95 the holding-jaws of the sliding spindles of the carrier are operated and also showing a detail section of the sliding bar which carries the cams by means of which the pushers for the carrier are actuated. Fig. 27 represents 100 a detail section taken in the line L L of Fig. 26. Fig. 28 represents an enlarged broken rear view of the pivoted upright lever by means of which the pushers for the rotary

carrier are actuated. Fig. 29 represents an enlarged section, taken in the line M M of Fig. 2, showing the mechanism for cutting the forward end of the swaged needle-blank 5 to the proper length. Fig. 30 represents a section taken in the line N N of Fig. 29. Fig. 31 represents a horizontal detail section, taken in the line O O of Fig. 29, showing a section of the rotary spindle of the swaging-
 10 machine taken at right angles to that shown in Fig. 30. Fig. 32 represents a section, taken in the line P P, of Fig. 30, showing an end view of the rotary spindle of the swaging-machine. Fig. 33 represents a detail sectional view taken in the line Q Q of Fig. 29. Fig. 34 represents the face view of the gear-edged cam for actuating the rotary milling-spindle in the forward direction and of the cam for clamping the feed-wire. Fig. 35 represents
 15 a top edge view of the gear-edged cam and the cam connections. Fig. 36 represents a vertical section, taken in the line R R of Fig. 34. Fig. 37 represents a detail section taken in the line S S of Fig. 36. Fig. 38 represents
 20 a face view of the rotary cam by means of which the reciprocating cams which serve to actuate the sliding spindles of the rotary carrier are operated. Fig. 39 represents an edge view of the vertically-reciprocated sliding
 25 bar to which the said cams are bolted, and Fig. 40 represents the forward face of the same. Fig. 41 represents a view of the rear face of the rotary carrier. Fig. 42 represents a view of the forward face of the same with
 30 the spring-actuated pushers removed. Fig. 43 represents an enlarged section taken in the line T T of Fig. 1. Fig. 44 represents a side view of the cylindrical blank severed from the wire, and also an end view. Fig. 45 represents a side view of the blank after the first operation of the swaging-dies. Fig. 46 represents a side view of the blank after the second operation of the swaging-dies. Fig. 47 represents a side view of the finished blank.
 40 In the drawings, 10 represents the bed-frame of the machine, to which are secured the supporting-standard 11 and the swaging-head 12, provided with the three rotary swaging-spindles 13, 14, and 15, (see Fig. 3,) which
 45 are actuated for revolution by means of suitable pulleys 16, which pulleys are not shown in said Fig. 3, but are shown in other figures of the drawings. At the top of the swaging-head 12 is attached the frame-piece 17, which
 50 holds the wire-feeding mechanism, as shown in Fig. 5 and also shown enlarged in Fig. 10, the said frame-piece being provided with a slot 18, the sides of which form guideways 19
 55 19 for the reciprocating cross-head 20, which carries the clamping-jaws that serve to bring forward the feed-wire 21 from the coil, the said wire passing first through the stationary guide-tube 22, thence through the opening 23 in the reciprocating cross-head, and thence
 60 between the clamping spring-jaws 24 of the tube 25, the said clamping-jaws being actuated to close upon the wire by means of the
 65 lever 26, pivoted to the cross-head on the pin 27, the said lever being forked at its upper end and provided with the adjusting-screws 70 28 28, which bear against the opposite sides of the cross-bar 29 of the lever 30, formed of the connected parallel arms 31 31, which lever is pivoted at its upper end to the top of the bracket 32 and is yieldingly connected at 75 its lower end to the sliding head 33 by means of the cross-piece 39, (shown separately in top view in Fig. 14,) to the ends 34 34 of which the lever 30 is jointed, the oppositely-projecting cylindrical arms 35 35 being loosely held in the cylindrical chambers 36 36 at opposite sides of the transverse notch 37, and at the ends of the cylindrical arms 35 35 are placed the spiral springs 38 38, by means of which the yielding engagement of the lever 80 30 with the sliding head 33 is effected. The wire is forced by means of the clamping-jaws 24 of the feeding-carrier through the passage 40 and between the clamping-jaws 41, (see Fig. 23,) the said jaws being actuated to clamp 90 the feed-wire 21 with a yielding pressure by means of the pressure-shoe 42, the upper portion of which is of smaller diameter than the lower portion, thus forming a shoulder 43, against which the spiral spring 44, which is held upon the upper portion of the pressure-shoe, is caused to bear, and upon the upper end of the said pressure-shoe is placed the loose cap 45, the said cap being made to rest upon the upper end of the said spring 44, so 100 that the downward movement of the cap, by means of the lever 46, will serve to impart a yielding pressure upon the wire held between the clamping-jaws. The lever 46 is actuated by means of the wiper-cam 47, in connection 105 with the downwardly-curved end of the said lever 46, the said wiper-cam 47 being attached to the rock-shaft 48, which shaft is actuated by means of the toothed arm 49 (see Figs. 15, 16, and 34) and the upright sliding bar 50, provided at its upper end with the rack-teeth 51 and bearing at its lower end upon the edge cam 52, held to turn loosely upon the fixed stud 53, the said sliding bar 50 being held against the said cam by means of the spring 110 54. (Shown in Fig. 34.) The feed-wire is fed forward through the stationary cutting-die 55 and through the movable cutting-die 56, held in the sliding head 57, the downward movement of which serves to cut the needle-blank from the wire and transfer it to a position for engagement with the jaws of the sliding spindles of the carrier. When the wire 21 has been fed forward by the action of the feeding-clamp and then held by the stationary clamping-jaws 41, the milling-tool 59 of the sliding rotary spindle 60 (see Figs. 15, 16, and 17) is brought forward to true up the forward end of the feed-wire, which serves to form the rear end of the needle-blank. The 120 said sliding rotary spindle 60 is held in the horizontal spindle-holding arm 61, pivoted upon the fixed bracket 62, the said arm being clamped to the said bracket by means of the 125 130

bolt 63 and the said bracket being provided with the open notch 64, adapted to receive the said bolt, whereby the spindle-holding arm 61 may be turned by hand from its normal horizontal position to the vertical position, as indicated by the dotted lines in Fig. 17, in order to obtain ready access to the end of the rotary spindle 60 for the purpose of removing the milling-tool 59 or inserting a milling-tool in the tool-holder 66 of the spindle, the said tool-holder being shown enlarged in Figs. 18 and 19 and in enlarged section in Fig. 22, the operation of the screw-cap 67 upon the slotted conical portion 68 of the tool-holder being such as to cause the milling-tool 59 to be firmly held for rotation with the spindle, the said milling-tool being provided with a beveled edge 69, whereby the end of the wire 21 will be trued up in conical form, as shown in Fig. 21. Within the cylindrical bore 71 is secured the bearing-sleeve 72, and at the rear of the said fixed bearing-sleeve is placed the loose sleeve 73, and between the pulley 74, attached to the spindle and sleeve 73, is placed the spiral spring 75, which is adapted to carry the spindle to its rearward position. The rear end of the rotary spindle 60 bears against the inner face of the lever 76, which is pivoted at the point 77 to the spindle-holding arm 61, and the said rotary spindle is actuated in the forward direction to bring the cutting-tool into action by means of the cam 78, secured to the rock-shaft 48. The downward movement of the sliding bar 57 serves to cut off the needle-blank from the continuous feed-wire and carry it downward to a position in front of the forcer 79, a guide-rest 80 being provided to support the projecting end of the blank. The forcer 79 is provided with a collar 81, against which the spiral spring 82 presses, and with an adjustable rack 95, the rearward movement of the forcer being effected by means of the cam 83, secured to the rock-shaft 84, the said rock-shaft 45 being actuated by means of the rotary cam 85, secured to the hub of the cam-wheel 86, the said cam 85 being caused to act upon the roller 87 upon the lever 88, to the outer end of which is jointed the connecting-rod 89, by means of which connection is made to the outer end of the arm 90, secured to the said rock-shaft 84. The rocking movement of the cam 83 causes the up-and-down movement of the rack 91, which engages with the teeth of the gear-pinion 92 upon the shaft 93, as shown in Figs. 29 and 33, and upon the shaft 93 is secured the gear-pinion 94, which engages with the teeth of the rack 95, held adjustably upon the shank of the forcer 79, by means of which the blank 60 may be moved forward and placed between the holding-jaws of the rotary carrier 96, the said rotary carrier being provided with the series of sliding spindles 97, each provided with the split holding-jaws 98 and with a forcer 99, (see Fig. 15,) by means of which the completed blank is to be discharged, the said holding-jaws being closed upon the inserted

blank by means of the conical end 100, which is embraced by the conically-bored head 101, secured to the outer tube 102 of the sliding spindle of the carrier. Within the bore of the outer tube 102 is placed the jaw-holding spindle 103, to the end of which the holding-jaws 98 are secured, and within the longitudinal hollow of the spindle 103 is placed the forcer 99, the forward portion 104 of which is made concentric, while the rearward portion 105 is eccentric and provided at its rear end with a projecting lug 106, by means of which the said forcer may be actuated in a forward direction, and having a spiral spring 107 at its forward concentric portion adapted to cause the rearward movement, the said forcer being caused to move forward to discharge the finished article by the engagement of the lug 106 with the fixed cam 108. (Shown in Figs. 8 and 9.) The jaw-holding spindle 103 is forced forward to close the holding-jaws upon the blank by means of the wedge 109, which is forked, as shown in Fig. 25, to receive the eccentric portion 105 of the forcer, the said wedge being caused to act upon the antifriction-roller 110, and thus force the tapered holding-jaws 98 forward into the conically-bored head 101, and thus closing the jaws upon the blank by means of the spiral spring 111, which is held upon the cylindrical shank 112 of the wedge between the loose rectangular washer 65 and the elongated shoe 113, secured to the lower end of the shank 112 and loosely held in the slot-opening 118 of the carrier, and the releasing or opening movement of the holding-jaws is effected by means of the fixed cam 114, located at the upper side of the sleeve 115, the shoe 113 coming in contact with the said cam at every revolution of the carrier, and thus causing the outward movement of the wedge against the inwardly-directed action of the spring 111. The outer end of the wedge 109 is held in a slot-opening 116 made in the outer tube 102, and the rectangular washer 65 is held in place by means of the shoulders 88, so that the outer tube 102 will form the required base for the action of the wedge to cause the forward movement of the jaw-holding spindles 103 within the bore of the outer tube 102.

Upon the outer tube 102 is placed the collar 117, which serves to limit the backward movement of the sliding spindle, the said backward movement being effected by means of the sliding head 33, which is held upon the shaft 119, to which the carrier 96 is secured and controlled in its movement by the guide 120, which serves to hold the sliding head in its vertical position. The shaft 119 is made hollow for part of its length to receive the sliding spindle 121, which is connected with the sliding head by means of the screw-threaded sleeve 122, through which the spindle passes, and between the collar 123, which rests against the shoulder 124 and the inner end of the sleeve, is placed the spiral spring 125, and between the nut 126 and the

outer end of the sleeve is placed the spiral spring 127. The sliding spindle 121 is thus yieldingly connected to the sliding head. The forward end of the sliding spindle is provided 5 with the cross-pin 128, which passes through the diametrically opposite slots 129 in the shaft 119 and into the hub of the disk-arms 130, the ends of which are provided with the sliding spring-actuated pushers 131, provided 10 at their outer ends with a head 132, against which the spring 133 is arranged to act, the said head 132 being held by the said spring in engagement with the washer 65, which is in engagement with the sliding spindle of the carrier. The forward-and-backward movement 15 of the sliding head 33 and the sliding spindle 121 is effected by means of the forked lever 134, to which is jointed the connecting-rod 135, the said connecting-rod being jointed 20 to the lever 136, which is actuated by means of the grooved side cam 137, bolted to the reciprocating bar 138, and the stud 139 and antifriction-roller 140, which engages with the slot of the cam. The reciprocating bar 25 138 is actuated in its up-and-down movement by means of the cam-groove 141 in the face of the cam-wheel 86 and the antifriction-roller 142, held upon the stud 143. The upper end of the lever 136 is provided with the bearing-shoe 144, (see Fig. 5,) which serves by engagement with the rear end of the lower sliding spindle 97 of the rotary carrier to impart forward movement to the said spindle. The reciprocating bar 138 is also provided with 30 the attached cams 145 and 146, which act upon the antifriction-rollers 147 and 148 (see Figs. 8, 36, and 37) of the levers 149 and 150, the said levers being pivoted upon the rod 151 and actuated toward the face of the cams 35 40 by means of spiral springs 152 and the bearing-shoes 153. The upper ends of the levers 149 and 150 are provided with the bearing-shoes 154 and 155, which are adapted for engagement with the rear ends of the sliding spindles of the rotary carrier which lie in the horizontal plane of the axis of the shaft 119, to which the carrier is attached, so that upon the upward movement of the reciprocating bar the several sliding spindles of 45 50 the carrier (except the upper one) will be carried forward for the proper insertion of the blanks between the swaging-dies. The shaft 119 is rotated intermittently by means of the gear-segment 156, secured to the hub 55 of the cam-wheel 86, (see Fig. 5,) the said gear-segment engaging with the gear 157, secured to the shaft 119, and to the hub of the gear 157 is secured the disk 158, provided upon its edge with the notches 159, adapted 60 to receive the projection 160 of the spring-actuated pawl-lever 161, the said pawl-lever being thrown out of engagement with the notch 159 by means of the cam 162, which engages with the arm 163 of the said lever just 65 prior to the engagement of the teeth of the gear-segment with the teeth of the gear 157, by means of which the shaft is rotated, and

by means of the notched disk and pawl-lever with the actuating-spring 167 the sliding spindles of the rotary carrier are held successively in line with the axes of the swaging-dies. The swaging-dies 164 are held in a diametrical groove 165, made in the enlarged head 166 at the forward end of the rotary swaging-spindle 15, as shown in Figs. 30 and 32, the beating-rollers 168 being held in cylindrical recesses made in the solid frame, and the beating-hammers 169 being arranged between the beating-rollers and the swaging-dies. The swaging-spindle shown in Figs. 29, 30, and 31 is the one of the series by means of which the needle-blank is finished and its end cut off to the required length. The swaging-spindle 15 is made hollow and provided with the driving-pulley 16, and within the 85 hollow of the swaging-spindle is held the steel tube 171, provided with the transverse opening 172, in which is placed the sliding cutter 173 for severing the wire of the blank, the said cutter being operated to cut off the end 90 of the finished blank by means of the cam-lever 174, the face 175 of the cam being held out of engagement with the projecting ends of the sliding forceps 176, arranged at opposite sides of the cutter and by means of which 95 the said cutter is operated, the said forceps being held in diametrical perforations made in the swaging-spindle, and upon the engagement of the projecting end of one of the forceps with the face of the cam the corresponding end of the opposite forceps will be thrown outward with the recess 177, so that the resulting movement of the cutter will serve to sever the wire at the contracted aperture 178 in the end of the tube 171, the cutter being 100 immediately returned to its normal position by the passage of the end of the forceps out of the recess 177 upon the continued revolution of the swaging-spindle, the said cutter and forceps taken together being made to fit 105 the cylindrical bore in which the spindle revolves. The cam-face 175 is held out of engagement with the ends of the forceps by means of the spiral spring 179 and its sliding shoe 180, the said spring acting against the 110 under side of the cam-lever 174 to press it against the stop-shoulder 182, and the cam-face 175 is thrown into a position for engagement to cut off the wire of the blank by means of the cam-operated bar 183, which carries 115 the rack 91. The desired adjustability of the movement to be imparted to the cam-lever 174 is effected by means of the adjusting-screw 184.

In front of the swaging-dies are placed the 125 guides 185, adapted to receive the forward ends of the sliding spindles 97 of the rotary carrier, and thus firmly hold the same in proper alignment with the dies, and the said guides may be provided with the side notches 130 186 in order to provide for the projection of the blank operated upon from the holding-jaws of the sliding spindles of the carrier, so that the needle-blank need not be drawn back-

ward to clear the extreme limit of the guides in order to provide for the continued forward movement of the carrier-spindles.

The downward movement of the sliding head 57, which carries the cutting-die 56 for severing the initial blank 9 from the feed-wire, is effected by means of the arm 191, secured to the rock-shaft 84, the said arm being provided with a stud 192, which enters the slot 193 made in the sliding head, the said slot being so formed that upon the initial downward movement of the outer end of the arm 191 a corresponding downward movement will be imparted to the sliding head, but when the extreme downward position has been reached, as determined by the adjustable stop-nuts 194, the movement of the arm 191 will continue, the stud 192 passing into the downwardly-curved portion of the slot 193 without imparting further movement to the sliding head.

The driving-cams are actuated by means of the cone-pulley 187 upon the shaft 188, at the opposite end of which is secured the gear-pinion 189, engaging with the teeth of the gear 190 at the edge of the cam 85.

In the operation of the machine the milling-tool 65 is brought forward to true up the end of the feed-wire 21, and then the downward movement of the sliding head 57 serves to cut off the initial cylindrical blank from the wire and carry it down to a position in front of the forcer 79, with the outer end of the blank resting upon the guide-rest 80. The forward movement of the said forcer will then carry the blank 9 forward to a position between the holding-jaws 98 of the sliding spindle 97 of the rotary carrier 96, as shown in Fig. 15, the said jaws being opened to receive the blank by means of the cam 114, and upon the subsequent rotary movement of the carrier by means of the gear-segment 156 the blank will be carried by the holding-jaws to a position in front of the dies of the rotary swaging-spindle 13. Then the action of the cam 145, attached to the reciprocating bar 138, will cause the forward movement of the carrier-spindle 97, the projecting forward end of the said spindle passing into the cavity of the guide 185, which serves to hold the said end so that the blank to be operated upon will be held in true line with the axis of the dies, and simultaneously with the forward movement of the carrier-spindle 97 by the action of the cam 145 the action of the cam 137 upon the lever 136 will cause the backward movement of the sliding head 33, and the connected spring-actuated pusher 131, which serves to hold the rear end of the carrier-spindle in close contact with the bearing-shoe 144 of the lever 136, and by means of the yielding pusher 131 variable forward movement may be imparted to the carrier-spindle under a uniform yielding pressure. When the blank has been operated upon by the dies of the swaging-spindle 13, and thus reduced from the cylindrical form shown in Fig. 44 to

the form shown in Fig. 45, and the direction of the movement of the cam 137 reversed, causing the withdrawal of the blank from the swaging-dies, the action of the rotary gear-segment 156 will cause the rotation of the carrier, so that the blank will be carried to a position in front of the swaging-spindle 14. Then the action of the reciprocating cam 137 upon the lever 136 will effect the forward movement of the carrier-spindle 97 to carry the blank between the dies of the said swaging-spindle to cause the further reduction of the form of the blank to the form shown in Fig. 46, and upon the withdrawal of the blank from the said dies by the downward movement of the cam 137 the continued rotary movement of the carrier will carry the blank to a position in front of the swaging-spindle 15, and the action of the cam 146 upon the lever 150 will serve to carry the blank between the swaging-dies of the said spindle, and by means of the said dies the blank will be still further reduced and extended, as shown in Fig. 47, and its end trimmed to the required length by means of the sliding cutter 173. The blank is then withdrawn from the dies by the downward movement of the cam 137, and upon the continued rotation of the carrier the shoe 113 of the wedge 109 will engage with the cam projection 114, whereby the holding jaws 98 will be opened to release the blank, and at the same time the lug 106 will engage with the fixed cam 108 to effect the forward movement of the forcer 99 to cause the discharge of the finished blank from the jaws preparatory to the reception of a fresh cylindrical blank as before.

By the employment of the fixed cam 108 for discharging the finished blank when the carrier is in motion instead of discharging the blank when the carrier is at rest I am enabled to dispense with one of the sliding spindles which would otherwise be required in the carrier, which constitutes a desirable improvement.

Any desired number of rotary swaging-spindles may be employed in combination with a rotary carrier having sliding spindles and holding-jaws for transferring blanks from the swaging-dies of one rotary spindle to the swaging-dies of another spindle in connection with means for inserting the blank between the holding-jaws, and means for discharging the finished blank.

I claim as my invention—

1. In a machine for making needle-blanks or similar articles, the combination of means for feeding the wire forward, and clamping means for holding the wire in its forward position, with a rotary cutter for milling the forward end of the wire, the reciprocating carrier provided with a cutting-die adapted to hold the milled blank when severed from the wire, and the forcer for forcing the severed blank endwise and forwardly from the cutting-die, when the carrier is in its delivering position, substantially as described.

2. In a machine for making needle-blanks or similar articles, the combination of means for feeding and clamping the wire, with a rotary cutter for milling the end of the wire, 5 the reciprocating carrier provided with a cutting-die for severing the wire to form the initial blank, the sliding forceer, means for actuating the said carrier to transfer the initial blank to a position in front of the forceer, the 10 rotary carrier provided with the sliding spindles and the holding-jaws, and means for actuating the sliding forceer to cause the transfer of the blank from the carrier to the holding-jaws of the spindles of the rotary carrier, substantially as described. 15
3. In a machine for making needle-blanks or similar articles, the combination of the reciprocating carrier provided with a cutting-die for severing the wire to form the initial 20 blank, the sliding forceer, the rotary carrier provided with the sliding spindle and the holding-jaws, and the guiding-rest for the blank intermediate of the end of the forceer and the holding-jaws of the spindles of the 25 rotary carrier, substantially as described.
4. In a machine for making needle-blanks or similar articles, the combination of the rotary carrier provided with a plurality of sliding spindles and holding-jaws, with the plurality 30 of rotary swaging-heads, means for actuating the spindles of the carrier to carry the blanks into and out of the range of the swaging-dies of the rotary swaging-heads, and means for imparting an intermittent rotary 35 movement to the carrier, substantially as described.
5. In a machine for making needle-blanks or similar articles, the combination of a rotary head provided with swaging-dies, and 40 beaters for actuating the swaging-dies, with the cutting-dies and means for operating the same, whereby the blanks may be made of uniform length when finished, substantially as described. 45
6. In a machine for making needle-blanks or similar articles, the combination of the sliding cross-head, and the clamping means for feeding the wire forward, clamping means for holding the wire in its forward position, the 50 lever for operating the sliding cross-head, and the opposite springs which form a yielding connection in both directions between the lever and its actuating means, with the rotary cutter for milling the end of the wire 55 when held by the clamping means, the reciprocating carrier provided with the cutting-

die adapted to hold the blank when severed from the wire, and the forceer for forcing the severed blank endwise from the cutting-die, substantially as described. 60

7. In a machine for making needle-blanks, the combination of the rotary hollow shaft, provided with the slot, and the rotary carrier provided with the sliding spindles and the holding-jaws, the sliding spindle within the 65 hollow of the shaft, the reciprocating cross-head sliding upon the shaft, the yielding connection between the cross-head and the sliding spindle, the sliding disk-arms connected with the sliding spindle through the slot of the shaft, the springs and the spring-actuated sliding pins, adapted to cause the backward movement of the spindles and holding-jaws of the carrier, and means for imparting forward movement to the said spindles and 70 holding-jaws, substantially as described. 75

8. In a machine for making needle-blanks or similar articles the combination of the rotary carrier provided with the sliding spindles, each provided with holding-jaws and with a forceer-spindle for discharging the finished blank from the holding-jaws, the springs for holding the forceer-spindles in their rearward positions, the stationary cam projection for opening the holding-jaws of the sliding 85 spindles, and the stationary cam for imparting forward movement to the forceer-spindles for discharging the finished blank while the carrier is being rotated, substantially as described. 90

9. In a machine for making needle-blanks, the combination of the rotary carrier provided with the sliding spindles, and the holding-jaws, with the reciprocating cams, the rotary cam for imparting the reciprocating motion to the said cams, and the cam-actuated levers, adapted to impart forward movement to the sliding spindles and holding-jaws of the carrier, substantially as described. 95

10. In a machine for making needle-blanks or similar articles, the combination of the rotary carrier provided with a plurality of sliding spindles and holding-jaws, with a plurality of rotary swaging-dies, means for actuating the spindles of the carrier to carry the 100 blanks into and out of the range of the swaging-dies and the guides for holding the sliding spindles in line with swaging-dies. 105
